UNITED STATES PATENT OFFICE.

THORE R. E. RUNDQVIST, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed November 21, 1924. Serial No. 751,237.

This invention relates to drilling mechanism.

It has for its object to provide an improved drilling mechanism. The improved 5 drilling mechanism to which my invention is particularly applicable comprises generally a vertical standard having guided thereby a vertically movable frame which carries a reciprocating cylinder and a piston disposed therein to which is attached a hollow drill steel so that upon reciprocation of the cylinder said steel will be reciprocated through fluid pressure generated within the cylinder due to relative movement between 10 the same and the piston. In this type of mechanism it is sometimes desirable to rotate the steel independently of reciprocation thereof such as when drill bits are removed or secured to the drill rods through a usual 15 threaded connection and it is an object of my invention to provide improved means for accomplishing this function. A further object is to provide improved means whereby the pressure generated within the cylinder during the reciprocation of the drill 20 rod may be relieved.

In the accompanying drawings I have shown for purposes of illustration one form which my invention may assume in practice.

In these drawings,—

Fig. 1 is an end elevation, partially in section, of the drilling mechanism mounted upon a wheeled support.

Fig. 2 is a vertical section through the standard.

Fig. 3 is a sectional view of the actuating piston and cylinder with my improved means for relieving the pressure generated 40 therein.

Fig. 4 is a horizontal section on line 4—4 of Fig. 2.

Fig. 5 is a vertical section on line 5—5 of Fig. 4.

Fig. 6 is an enlarged detail of the means for preventing reciprocation of the drill steel during rotation thereof.

I have shown my invention embodied in a drilling mechanism of the type disclosed 50 in a copending application of Henry H. Mercer, Ser. No. 472,546, filed May 25, 1921 in view of which it is thought only necessary to briefly describe the same. The mechanism comprises a pair of vertical channel iron standards 1 and 2 mounted upon suit-

able frame work 3 constituting part of a wheeled support 5. Slidably guided by the standards 1 and 2 is a frame comprising upper and lower heads 6 and 7, respectively, connected and held in spaced relation by suitable spacing rods 8. Mounted upon the upper head is a crank shaft 9 adapted to actuate, as through a connecting rod 11, a crosshead 12 slidably supported by a suitable crosshead support 13. Rigidly carried by the crosshead 12 and depending therefrom is a cylinder 14 comprising a lower head 15 and a pair of upper heads 16 and 17 which provide a pressure fluid storage chamber 18. A piston 19 reciprocably mounted within the cylinder has a piston rod 20 depending therefrom which extends through and has a splined connection 21 with a hub 22 of a worm wheel 23 rotatably mounted within the head 7.

The worm wheel constitutes a part of the rotation mechanism which will be later described and forms a part of the present invention. Connected as by a collar 24 to the lower end of the piston rod is a hollow drill steel 25 to which any suitable type of bit 26 may be threadedly connected. Meshing with the worm wheel is a worm 27 rotatably mounted within the lower head 7 and having a ratchet 28 disposed on the outer end of the worm shaft 29, while a pawl 30 is suitably mounted within an arm 31 mounted upon the shaft 29. The free end of said arm is connected to the lower head 15 as by a suitable connecting link 32 so that upon positive reciprocation of the cylinder 14 said pawl and ratchet mechanism will cause intermittent rotation of the hollow drill steel.

Pivottally mounted upon the lower side of the head 7 is a finger 33 having an actuating handle 34 adapted to be held in one of a plurality of positions as by a usual thumb operated pin and slot connection 35 shown in Fig. 6. The plurality of notches shown 95 are adapted to permit holding the steel at different elevations to facilitate any operation thereon which might be deemed necessary such as removing or replacing the drill bit 26. The finger 33 when operative is disposed within an annular recess 36 formed in the upper end of the collar 24 so that it is possible to hold the steel against reciprocation and upon continued positive reciprocation of the cylinder to cause the rota- 100 105 110

tion of the steel through the pawl and ratchet mechanism. It is to be noted in Fig. 5 that the pawl and ratchet mechanism is of the reversible type so that drill steel rotation may be had in either direction for the proper screwing or unscrewing of the drill bits on or off the rod 25.

It is not thought necessary to go into detail as to the particular means for actuating the crank shaft 7 or for raising and lowering the frame carrying the cylinder and piston 14 and 19. As said means does not enter into the present invention it will suffice to say that during raising of said frame it is possible to continuously drive the crank shaft 9 as clearly disclosed in the above mentioned copending application.

During reciprocation of the cylinder while the steel is held against reciprocation it may be desired to relieve the pressure which would otherwise be generated from the cylinder 14. This means comprises suitable valves 36 and 37 having communication respectively with the cylinder 14 and the chamber 18, these valves being adapted to be simultaneously actuated as through suitable lever arms 38 and links 39 connected to diametrically opposite points of a manually controlled lever pivotally mounted upon the side of the cylinder 14. The exhaust valve mechanism as described in the application mentioned above is shown at 41 while inlet valves are indicated at 42, thus by proper manipulation of the handle 40, valves 36 and 37 are adapted to relieve the before mentioned pressure which would otherwise be continuously generated due to the continuous reciprocation of the cylinder and operation of valves 41 and 42.

In case it should be desired to pass cleansing fluid through the hollow steel while the steel is stationary, the valves 36 and 37 could be closed, in which case pressure would be generated and stored within the chamber 18 from whence it would pass through ports 43 disposed within a sleeve 44 extending upwardly from the lowermost portion of the head 16 and into a hollow member 45 extending upwardly from the piston 19 and having telescopic engagement with the member 44 and an associated packing member 46.

The general mode of operation it is thought will be apparent from the previous description, but to epitomize, the crank shaft 19 is continuously operated to continuously reciprocate cylinder 14 and in normal operation, also reciprocate the piston 19 and steel as by fluid pressure generated within the cylinder and normally transmitted to chamber 18 and therefrom through the hollow drill steel to the bottom of the hole from which it would blow the cuttings. When it is desired to remove the drill bit 26 the frame constituting heads 6 and 7 would be raised and the handle 34 operated to place

the finger 33 in the recess 36 to hold the steel against reciprocation during continued operation of the cylinder 14. This continued reciprocation of the cylinder would cause continued rotation of the drill steel to the pawl and ratchet mechanism 28 and 30 actuated by the arm 31 operatively connected to the cylinder 14 by the link 32. Should it be desired to relieve the pressure generated within the cylinder, the handle 40 will be rotated to relieve the pressure within the chamber 18 and cylinder 14.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A drilling mechanism comprising relatively reciprocable cylinder and piston elements, means cooperating with one of said elements for effecting reciprocation of the other of said elements, a drill rod reciprocable with one of said elements, means for rotating said drill rod, and means for holding said element with which said drill rod is reciprocable against reciprocation while rotation of said drill rod and reciprocation of the other element are continued.

2. A drilling mechanism comprising relatively reciprocable cylinder and piston elements, means cooperating with one of said elements for effecting reciprocation of the other of said elements, a drill rod reciprocable with one of said elements, means for rotating said drill rod, and means for positively holding said element with which said drill rod is reciprocable against reciprocation while rotation of said drill rod and reciprocation of the other element are continued.

3. A drilling mechanism comprising a piston, power operated means for effecting reciprocation of said piston including a cylinder, a drill rod reciprocable with said piston, means operatively connected to said power operated means for rotating said drill rod, and means for holding said piston against reciprocation while rotation of said drill rod and reciprocation of said cylinder are continued.

4. A drilling mechanism comprising a piston, means for effecting reciprocation of said piston including a cylinder, a drill rod reciprocable with said piston, means operatively connected to said cylinder for rotating said drill rod, and means for holding said piston against reciprocation while rotation of said drill rod and reciprocation of said cylinder are continued.

5. A drilling mechanism comprising a piston, power operated means for effecting re-

ciprocation of said piston including a cylinder, a drill rod reciprocable with said piston, means operatively connected to said power operated means for intermittently rotating said drill rod, and means for positively holding said piston against reciprocation while rotation of said drill rod and reciprocation of said cylinder are continued.

6. A drilling mechanism comprising a piston, power operated means for effecting reciprocation of said piston including a cylinder, a drill rod reciprocable with said piston, means operatively connected to said cylinder for intermittently rotating said drill rod, and means for positively holding said piston against reciprocation while rotation of said drill rod and reciprocation of said cylinder are continued.

7. A drilling mechanism comprising a piston, power operated means for effecting reciprocation of said piston including a cylinder, a drill rod reciprocable with said piston, means including a ratchet mechanism operatively connected to said cylinder for intermittently rotating said drill rod, and means for positively holding said piston against reciprocation while rotation of said drill rod is continued.

8. A drilling mechanism comprising a cylinder and a piston therein, means for effecting reciprocation of said cylinder and piston, a drill rod reciprocable with said piston, means for rotating said drill rod, and means for holding said piston against reciprocation while rotation of said drill rod and reciprocation of said cylinder are continued.

9. A drilling mechanism comprising a cylinder and a piston therein, power operated means for effecting reciprocation of said cylinder and piston, a drill rod reciprocable with said piston, means operatively connected to said power operated means for rotating said drill rod, and means for holding said piston against reciprocation while rotation of said drill rod and reciprocation of said cylinder are continued.

10. A drilling mechanism comprising a cylinder and a piston therein, power operated means for effecting reciprocation of said cylinder and piston, a drill rod reciprocable with said piston, means operatively connected to said cylinder for rotating said drill rod, and means for holding said piston against reciprocation while rotation of said drill rod and reciprocation of said cylinder are continued.

11. A drilling mechanism comprising a cylinder and a piston therein, means for effecting reciprocation of said cylinder and piston, a drill rod reciprocable with said piston, means for rotating said drill rod, and means for positively holding said piston against reciprocation while rotation of said drill rod and reciprocation of said cylinder are continued.

12. A drilling mechanism comprising a piston, power operated means for effecting reciprocation of said piston including a cylinder, a drill rod reciprocable with said piston, means operatively connected to said power operated means for rotating said drill rod, and means for interrupting reciprocation of said piston while rotation of said drill rod and reciprocation of said cylinder are continued.

13. A drilling mechanism comprising a cylinder and a piston therein, means for effecting reciprocation of said cylinder and piston, a drill rod reciprocable with said piston, means operatively connected to said cylinder for intermittently rotating said drill rod, and means for positively holding said piston against reciprocation while rotation of said drill rod and reciprocation of said cylinder are continued.

14. A drilling mechanism comprising a drill rod, means for effecting reciprocation of said drill rod including movable piston and cylinder elements, one of which is adapted to be positively actuated, means for rotating said drill rod independently of the reciprocation of one of said elements, and means for holding said piston against reciprocation during reciprocation of said cylinder and rotation of said drill rod.

15. A drilling mechanism comprising a drill rod, means for reciprocating said drill rod including movable piston and cylinder elements one of which is adapted to be positively actuated, means operatively connected to one of said elements for rotating said drill rod independently of the reciprocation of the other of said elements, and means for holding said piston against reciprocation during reciprocation of said cylinder and rotation of said drill rod.

16. A drilling mechanism comprising a piston, power operated means for effecting reciprocation of said piston including a cylinder, a drill rod reciprocable with said piston, means operatively connected to said power operated means for rotating said piston, said rotating means including gearing operatively connected to said drill rod, and means for holding said piston against reciprocation while rotation of said drill and reciprocation of said cylinder are continued.

17. A drilling mechanism comprising a piston, non-reversible power operated means for effecting reciprocation of said piston including a cylinder, a drill rod reciprocable with said piston, means operatively connected to said power operated means for rotating said drill rod in opposite directions, and means for holding said piston against reciprocation while rotation of said drill rod in either direction is continued.

18. A drilling mechanism comprising a cylinder and a piston therein, a non-reversible power operated means for effecting

115

120

125

130

reciprocation of said cylinder and piston, a drill rod reciprocable with said piston, means operatively connected to said cylinder for intermittently rotating said drill rod in opposite directions, and means for holding said piston against reciprocation while rotation of said drill rod in either direction is continued.

19. A drilling mechanism comprising relatively reciprocable cylinder and piston elements, means cooperating with one of said elements for effecting reciprocation of said other element, a drill steel reciprocable by one of said elements, means for rotating said drill steel, and means for positively holding said drill steel against reciprocation while rotation thereof and reciprocation of the other element are continued.

20. A drilling mechanism comprising a vertical standard, a sliding frame having upper and lower heads guided by said standard, a drilling tool, power operated actuating means for said tool comprising reciprocable cylinder and piston members, and gear operated tool rotation means operatively connected to said power operated actuating means and carried by the heads of said frame, said means including an element reciprocable with said cylinder.

21. A drilling mechanism comprising a cylinder and a piston therein, power operated means for effecting reciprocation of said cylinder and piston, a drill rod reciprocable by said piston, said cylinder and piston being adapted to generate fluid pressure, and means operable at will and adapted to be set in different positions for relieving the pressure generated in the opposite ends of said cylinder, said means including an adjustable relief valve constantly in communication with the cylinder bore.

22. A drilling mechanism comprising a cylinder and a piston therein, power oper-

ated means for effecting reciprocation of said cylinder and piston, a drill rod reciprocable by said piston, said cylinder and piston being adapted to generate fluid pressure, and means at opposite ends of the cylinder operable at will and adapted to be set in different positions for simultaneously relieving the pressure generated in the opposite ends of said cylinder.

23. A drilling mechanism comprising relatively reciprocable cylinder and piston elements, means cooperating with one of said elements for effecting reciprocation of the other of said elements, a drilling tool actuated by one of said elements, means for rotating said drilling tool, and means for holding one of said elements against reciprocation while reciprocation of the other element and rotation of the drilling tool are continued.

24. A drilling mechanism comprising a cylinder and a piston therein, means for effecting reciprocation of said cylinder and piston, a drill rod reciprocable with said piston, means operatively connected to said cylinder and including an element reciprocable therewith for rotating said drill rod, and means for positively holding said piston against reciprocation while rotation of said drill rod is continued.

25. A drilling mechanism comprising a piston, a power operated means for effecting reciprocation of said piston including a cylinder, a drill rod reciprocable with said piston, means operatively connected to said power operated means for intermittently rotating said drill rod while said power operated means continuously operates, and means for positively holding said piston against reciprocation while rotation of said drill rod is continued.

In testimony whereof I affix my signature.
THORE R. E. RUNDQVIST.
